VALVE GRINDING TOOL

Raymond A. Dougherty, Tucson, Ariz.

Application July 21, 1941, Serial No. 403,448

4 Claims. (Cl. 51—241)

My invention relates to improvements in tools for use in conjunction with poppet valves of internal combustion engines in grinding such valves.

The principal object of the invention is to provide a simply constructed tool for positively gripping the heads of said valves and providing a socket for accommodating a screw driver, or the like, for rotating the valve on its seat to grind the same.

Another object is to provide a device of the character and for the purpose above set forth which is easily and quickly applied, adapted for use with valves of different sizes and of either the dome or flat top variety, and which is inexpensive to manufacture.

To the accomplishment of the above, and subordinate objects presently appearing, a preferred embodiment of my invention has been illustrated in the accompanying drawing, set forth in detail in the succeeding description, and defined in the claims appended hereto.

In said drawing:

Figure 1 is a view in side elevation of the preferred embodiment of my improved tool applied to a poppet valve head.

Figure 2 is a view in top plan.

Figure 3 is a view in perspective of one of the clips.

Figure 4 is a view in perspective of the block in its preferred embodiment.

Figure 5 is a view illustrating blocks of different sizes in top plan.

Reference being had to the drawing by numerals, in its preferred embodiment my improved tool comprises a rectangular socket forming block 1 provided with a central top slot 2 therein functioning as a kerf for a screw driver, or other implement, not shown, said block having a central through bolt hole 3 therein as best shown in Figure 1. The block 1 may be formed of any suitable metal and is of a size to fit within the confines of the head 4 of a poppet valve 5 on top of said head.

A pair of duplicate, elongated, blade-like clips, or clamps, 6 of resilient metal are provided for securing flat to opposite sides of the block 1, respectively, said clips being each provided with a central bolt hole 7 therein. For securing the clips 6 to said block 1, a bolt 8 is provided to extend through the clips 6 by way of said bolt holes 7 and through the block 1 by way of the bolt hole 3, said bolt being provided with a nut 9 and lock washer 10 thereon.

The clips 6 are of a length to span the top of

the valve head 4 to extend edgewise thereover at opposite sides of the block 1 and are provided, respectively, with a pair of downwardly and inwardly inclined lower edge prongs 11 at opposite ends thereof, respectively, adapted to bite into the upper edge rim 12 of the valve head 4.

As best shown in Figures 1 and 2, the distance between the prongs 11 of each pair is sufficiently less than the diameter of the valve head rim 12 so that when said clips 6 are drawn tight by the bolt 8 and nut 9 against the block 1, said clips are flexed inwardly toward each other to clampingly engage the prongs 11 sidewise against the rim 12 and thereby cause said prongs to bite into said rim and anchor the block to the valve head 4 in the center thereof. The clips 6 are provided with lower concave edges 13, whereby they are adopted for use with either flat top valve heads 4 such as shown, or, those having dome like tops.

For different sizes of valve heads longer blocks such as shown at 14, but, otherwise identical with that already described, may be provided to space the clips 6 further apart and thereby adapt the same to clamp against valve heads of larger diameters.

The manner in which the described invention is applied and used will be readily understood. With the nut 9 loosened, the block 1 is positioned upon the valve head 4 and the clips 6 are moved inwardly, or toward each other, over said head 4 until the prongs 11 engage the rim 12. The nut 9 is then tightened to flex the clips 6 inwardly and force the prongs 11 tight against the rim 12. Under said flexing of the clips 6 the prongs 11 are caused to bite laterally into said rim 12 and are drawn together, in each pair, and thereby caused to bite tangentially edgewise into the rim 12 as will be clear. A screw driver, or hand valve grinding implement, not shown, may then be inserted in the slot 2 and the valve rotated through the medium of the described tool on its seat to grind the same in the usual manner.

The foregoing will, it is believed, suffice to impart a clear understanding of my invention without further explanation.

Manifestly, the invention, as described, is susceptible of modification without departing from the inventive concept and right is herein reserved to such modifications as fall within the scope of the appended claims.

Having described the invention, what is claimed as new is:—

1. A device of the class described for attachment to the head of a poppet valve comprising a block-like member adapted to be imposed on top

of said head and constructed and arranged to provide a tool grip, a pair of blade-like clips upon opposite sides of said member respectively, adapted to span said head and extend edgewise thereover for damping against opposite sides of the member, said clips being provided, respectively, with a pair of edge prongs at opposite ends thereof for biting into the rim of said head when clamped to said member, and manipulative means for clamping said clips to said member.

2. A device of the class described for attachment to the head of a poppet valve comprising a block-like member adapted to be imposed on top of said head and constructed and arranged to provide a tool grip, a pair of blade-like clips upon opposite sides of said member respectively, adapted to span said head and extend edgewise thereover for clamping against opposite sides of the member, said clips being provided, respectively, with a pair of edge prongs at opposite ends thereof for biting into the rim of said head when clamped to said member, and manipulative means for clamping said clips to said member, said means comprising a bolt extending through said member and clips and having a nut thereon.

3. A device of the class described for attachment to the head of a poppet valve comprising a block-like member adapted to be imposed on top of said head and constructed and arranged to provide a tool grip, a pair of blade-like clips upon

opposite sides of said member respectively, adapted to span said head and extend edgewise thereover for clamping against opposite sides of the member, said clips being provided, respectively, 5 with a pair of edge prongs at opposite ends thereof for biting into the rim of said head when clamped to said member, and manipulative means for clamping said clips to said member, said clips having concave lower edges adapting 10 the same to span dome top valve heads.

4. A device of the class described for attachment to the head of a poppet valve comprising a block-like member adapted to be imposed on top of said head and constructed and arranged to 15 provide a tool grip, a pair of blade-like clips upon opposite sides of said member respectively, adapted to span said head and extend edgewise thereover for clamping against opposite sides of the member, said clips being provided, respectively, 20 with a pair of edge prongs at opposite ends thereof for biting into the rim of said head when clamped to said member, and manipulative means for clamping said clips to said member, said clips having concave lower edges adapting 25 the same to span dome top valve heads, said member having a top kerf thereon for accommodating the bit of a screw driver or the like for rotating said device and valve to grind the same.

RAYMOND A. DOUGHERTY.
